UNITED STATES PATENT OFFICE

VICTOR R. DESPARD AND HANS C. R. POPP, OF VALPARAISO, INDIANA, ASSIGNEES TO
MCGILL MANUFACTURING COMPANY, A CORPORATION OF INDIANA

CONNECTING BLOCK FOR ELECTRIC-LIGHT CLUSTERS

Application filed June 3, 1927. Serial No. 196,260.

Our invention relates to connecting means for connecting the lamp sockets of electric lamp clusters with the conductors from the source of current, and has for its principal object the construction of a unit which may be inserted in the hollow body of the cluster and which will eliminate the necessity of providing a plurality of wiring connection between the conductors and the lamp sockets.

Another object of the invention is to provide a connecting means of this character which will maintain contact with the lamp sockets regardless of their position when such sockets are rotatably or rockably mounted on the hollow body of the cluster.

It is also a purpose of this invention to so construct the connecting means that it may be mounted in the hollow body as a unit, and when so mounted will be firmly fixed in place so that the connections for the lamp sockets cannot get out of alignment therewith and so that the conductors for supplying current may be readily connected to the unit before the sockets are put in position.

Other objects and advantages of the invention will appear as the description proceeds in connection with the accompanying drawings. However, we wish it to be distinctly understood that we do not intend to limit ourselves to the exact details shown and described, but we intend to avail ourselves of all such modifications as would occur to one skilled in this art and as fall within the scope of the claims.

In the drawings—

Fig. 1 is a side view partly in section of a lamp cluster with the improved connecting block mounted therein;

Fig. 2 is a horizontal section on line 2—2 of Fig. 1;

Fig. 3 is a vertical section taken centrally through the connecting block;

Fig. 4 is another vertical section illustrating the means for connecting the conductor to the block;

Fig. 5 is a perspective view of the insulating portion of the block;

Fig. 6 is a perspective view of the connecting elements removed from the block;

Fig. 7 is a side view of the switch mounted

on the block with the switch cover removed; and

Fig. 8 is a section on line 8—8 of Fig. 7.

Referring now in detail to the drawings, the numeral 10 indicates generally the supporting stem for the light cluster through which the conductors 11 and 12 extend into the hollow body 13 of the cluster. This hollow body supports a pair of lamp sockets 14 and 15, the construction of which is similar to that shown in our co-pending application, Serial No. 197,944, filed June 10, 1927, for electric light clusters. These sockets as shown in the co-pending application and at Fig. 1, are rotatably mounted in openings provided at opposite points in the hollow body, each of the lamp sockets being provided with a central terminal 16 and an annular terminal 17 surrounding the central terminal 16, these terminals as shown in Fig. 1 being located within the hollow body 13. Within the hollow body there is provided the U-shaped member 20 which as shown in Figs. 1 and 3 is connected at its lower end 21 to the supporting stem 10 for the cluster and serves to fix the hollow body in position thereon. The upper horizontal leg 22 of the U-shaped member 20 as shown in Fig. 1, is utilized to secure the top portion of the hollow body in place and in addition supports the mounting member 23 upon which a shade or other device may be secured.

Our improved connecting block consists of the insulating body portion 25 secured by means of the screw 26 to the vertically extending portion of the member 20 and as shown in Fig. 2, is provided with a groove 27 in the back thereof, this groove receiving the vertical portion of the member 20 so as to prevent any rocking of the connecting block about the screw 26. This connecting block at the top is provided with the grooves 28 and 29 receiving the terminal members 30 and 31, which are provided with screw-threaded openings to receive the screws 32 and 33 by means of which the conductors 11 and 12 are connected thereto. The member 30 as shown, has a down-turned portion 34 fitting in the groove 35 in the face of the connecting block, for a purpose which will presently appear.

Member 31 as shown clearly in Figs. 1 and 6 is adapted to fit into an angular groove 36 which extends horizontally from the groove 29 to a point near the center of the block and then extends downwardly and becomes deeper as at 37, to provide a seat for the vertically extending portion 38 of the member 31. At the end of the portion 38 the member 31 is provided with the outwardly extending portion 39 which projects out substantially to the face of the connecting block.

Extending horizontally across the face of the block substantially midway between the upper and lower edges thereof, is another groove 40 which, as shown in Fig. 2, has the deeper central portion 41 intersecting the groove 37 but being more shallow so that the portion 39 of the member 31 is spaced below the bottom of the groove 41. Adjacent the opposite end of the groove 40 there is provided the upwardly projecting portions 42 and 43 upon which the contact plates 44 and 45 are mounted, these plates being provided with downturned edges on the opposite sides thereof for fitting on the opposite sides of the projections 42 and 43, and also having the downturned ends 46 and 47 adapted to engage the inner end faces of the projections 42 and 43 to limit the outward movement of the members 44 and 45. These members are also provided with elongated slots 48 and 49 for a purpose which will presently appear. Seated within the deep portion 41 of the slot 40 is the coil spring 50 which, as shown, extends from the downturned end 46 of plate 44 to the downturned end of plate 45 and serves to yieldingly hold these plates extended outwardly so that their outermost ends will project beyond the end faces of the block 25. This spring also serves to electrically connect members 44 and 45, but due to the deep slot 37 the spring cannot contact with the member 38 and the terminal 31 is thus insulated from the members 44 and 45.

Within the slot 52 directly beneath the slot 40, there is provided a contact member 53 provided with the downturned inner end 54 fitting over the ledge or shoulder 55 where the slot 52 becomes deeper as it extends toward the center of the block. Within this deeper portion the spring 56 is seated, this spring being in contact with the downturned portion 54 and also with the lower end 39 of the member 38, so that the contact member 53 is directly connected by means of the portions 38 and 31 with the conductor 12. At the opposite end of the block from the member 53 there is provided another contact member 58 fitting in the slot 59 of the connecting block. The slot 59 is also provided with the deeper portion 60 within which the downturned end 61 of the member 58 fits, and the member 58 is held in the extreme outer position by means of the spring 62 seated within the deeper portion 60 of the slot 59. The

wall portion 63 between the slots 52 and 59 serves to effectually insulate the springs 56 and 62 from each other so that the contact-making member 58 is entirely insulated from any of the other contacts.

Any suitable means may be utilized for interconnecting the contact plates 44 and 45 and the terminal member 30 as well as interconnecting contacts 53 and 58. In the present instance the means provided consists of a switch similar to that shown in our co-pending application above referred to, which switch has a series of contact terminals 70, 71, 72 and 73 illustrated in dotted lines in Fig. 1 and engaging the contact plates 30, 45, 58 and 53 respectively, in the manner shown in the sectional view of Fig. 4. The switch casing itself is mounted upon the connecting plug 25 by means of a pair of screws 75 and 76 which extend through the block 25 and through the slots 48 and 49 provided in the members 44 and 45, thence through an insulating member illustrated at 77 which has a pair of inturned projections extending over the members 44 and 45, but otherwise consists of a narrow strip extending around the outer edge of the face of the block 25 as shown in Fig. 4. The screws then extend through the body portion 78 of the switch and are screw-threaded into the cover 79 thereof to firmly hold it in position. This switch may be of any suitable type for connecting the conductor terminals to the lamp sockets through the connecting block, but we prefer to use the type of switch shown in application, Serial No. 62,833, filed October 16, 1925, by Victor Despard on multiple series switch. This switch being of the rotatable stem 80 having means indicated generally by the numeral 81 for causing step by step rotation of the member 80 and with it the bridging contacts 82 and 83 mounted thereon over the stationary contacts 84, 85, 86 and 87 which connect with the members 70, 71, 72 and 73.

As shown in Fig. 7, the contact 86 is elongated to contact with the bridging contacts in two positions thereof and directly opposite the extended portion 88 of contact 86, is an insulated portion 89. Thus the switch as shown in Fig. 7 is moved into position to cut off the supply of current to sockets 14 and 15. In the next position of the switch, bridging contact 83 will connect contacts 86 and 87, while contact 82 will connect contacts 84 and 85. In such position current will be supplied through terminal 30, connecting contact 70, contact 84, bridging contact 82, contact 85, connecting contact 71 to members 45 and 44 and terminals 16 of the sockets. The return circuit running from terminals 17 to members 53 and 58, which are connected together by means of connecting contacts 72 and 73, contacts 80 and 87 and bridging contact 83,

and to the terminal 31 through spring 56 and portions 39 and 38.

From the above description it is thought that the construction and advantages of this device will be clear to those skilled in this art, and having thus described our invention what we claim and desire to secure by Letters Patent of the United States is:—

1. A connecting device of the character described comprising a base, conducting means thereon adapted for connection with a source of current supply, conducting means thereon adapted for connection with a translating device, means for interconnecting said conducting means, said second mentioned conducting means including a plurality of pairs of contacts slidably mounted in said base and projecting therefrom, and springs yieldingly maintaining said contacts in projecting position, one of said springs connecting a contact of one of said pairs of contacts with a contact of another pair, said connected pair of contacts being insulated from said first named conducting means.

2. A connecting device of the character described comprising a base, conducting means thereon adapted for connection with a source of current supply, conducting means thereon adapted for connection with a translating device and switch mechanism for selectively interconnecting said conducting means, said second mentioned conducting means including a pair of contacts projecting from a face of said base, said switch mechanism having means holding said contacts in position on said base.

3. A connecting device of the character described comprising a base, conducting means thereon adapted for connection with a source of current supply, conducting means thereon adapted for connection with a translating device and switch mechanism for selectively interconnecting said conducting means, said second mentioned conducting means including a pair of contacts projecting from a face of said base and slidably mounted thereon and said switch mechanism providing means for retaining said slidable contacts on said base.

4. A connecting device of the character described comprising an insulating base, a pair of terminals thereon for connection to a source of current supply, said base having one face thereof provided with a plurality of grooves, contact members seated in certain of said grooves and provided with portions adapted to connect with a consumption circuit, one of said members being permanently connected with one of said terminals, and means secured on the recessed face of said base for selectively connecting certain others of said contact members with said terminals.

5. A connecting device of the character described comprising an insulating base, a pair of terminals thereon for connection to a source

of current supply, said base having one face thereof provided with a plurality of grooves, contact members seated in certain of said grooves and provided with portions adapted to connect with a consumption circuit, means secured on the recessed face of said base for connecting said contact members with said terminals, and means in one of the grooves of said base electrically connecting a pair of said contacts together.

In witness whereof, we hereunto subscribe our names this 16th day of May A. D., 1927.

VICTOR R. DESPARD.
